CONDENSER

William Dubilier, New Rochelle, N. Y., assignor to
 Dubilier Condenser Corporation, New York,
 N. Y., a corporation of Delaware

Application October 12, 1932, Serial No. 637,415
 Renewed July 3, 1937

13 Claims. (Cl. 175—41)

This invention relates to condensers and similar electrical devices, and containers therefor, and more particularly to such devices when associated with a liquid, such as an insulating oil.

- 5 For the purposes of this specification the term "condenser" includes other electrical devices which will function when sealed within a container; and the term "oil" includes other liquid insulating or impregnating materials.
- 10 It is important that the condenser be well supported within its container, and the requisites of the container are that it keep the oil in, keep moisture out, and that it afford mechanical protection and support.
- 15 Two types of such containers are in common use, one of which is formed of thin sheet metal having its seams soldered, as in a sardine can, and is therefore limited to small and light weight devices. Containers of this type are cheap but
- 20 afford little mechanical protection to the device enclosed therein and they are easily damaged, with consequent leakage. The other type is made of heavy metal to provide an oil tight container with sufficient mechanical protection. The cost
- 25 of such containers is high, whether they are made with soldered or welded joints, or made seamless by drawing or casting; a large part of the cost being due to the necessity of making them tight to oil and moisture. Additional expense and diffi-
- 30 culty are involved in welding or soldering the cover on such a container due to the large amount of heat absorbed by the heavy metal walls and the danger of injuring the condenser therein. In either type the seams or joints are directly exposed to mechanical shocks which may break them and cause leakage.

The object of this invention is to make a container which is easily sealed to oil and moisture and which gives greater protection against leakage and mechanical shocks than either type aforementioned, at less cost than the heavy type and occupying about the same or less space. A further object is to support a condenser within the container in fixed, spaced relation to the walls.

The invention will be described in connection with the accompanying drawing showing one embodiment thereof and in which

50 Fig. 1 is a view partly in section, of a container with a condenser and its support therein, according to the invention;

Fig. 2 shows the external appearance thereof on a smaller scale;

Fig. 3 shows a support member; and

55 Fig. 4 is a fragmentary sectional view corre-

sponding to Fig. 1 but slightly spread and enlarged for clearness.

In the several figures like reference characters indicate like parts.

The container for the condenser shown in Figs. 5 1 and 2 is provided with double walls consisting of a thin metal can 1 and an outer enclosure 2 of heavy metal. Cushioning material is disposed between the inner and outer walls preferably at the top and bottom, as illustrated by spacers 3 10 and 4, of cork, rubber composition or the like. The can 1 should be a snug fit within the enclosure 2 with little space between their side walls, but if desired additional cushioning material may be inserted therebetween. The spaces 15 between the walls may be filled with melted compound indicated at 3a (Fig. 4), such as wax, in lieu of spacers 3 and 4 or in combination there- with.

Since the inner can 1 is made of thin metal, 20 such as tin, it is easily formed and soldered, thereby providing an oil and moisture tight enclosure for a condenser 5. The outer can 2 need not be oil tight, its chief purposes being to provide mechanical protection and support for the 25 inner can and the condenser. For this reason the enclosure 2 can be made very cheaply by bending up sheets of heavy metal and spot-welding the joints. A closure member or bottom cover 6 can be secured by a riveting or bending opera- 30 tion, or both. Preferably this cover consists of a metal plate having its sides 7 and 8 bent up to engage the corresponding sides 9 and 10 of enclosure 2 and having its end portions secured by eyelets 11 to projecting feet 12 and 13 of the enclosure. For additional security, the corners 14 35 of cover 6 are bent down to engage the upper sides of projections 12 and 13. The projecting feet are thus made doubly thick with triple thickness at the corners, to provide a rigid mounting 40 base for the device.

Fig. 3 shows details of a portion of a support or clamp which holds the condenser 5 and serves to space the condenser from the walls of can 1, at the same time preventing movement of the condenser within the container. The support comprises a U-shaped metal member 16 adapted to rest on the bottom of the container with its sides fitting between opposite walls thereof and with extensions 17 and 18 on its bottom portion fitting 50 between the other two walls of the container. The condenser 5, as shown in Fig. 1, usually consists of a number of oil filled sections 19 stacked one above the other, each section having foils of opposite polarity exposed at opposite ends 55

thereof. These condenser sections are stacked in the member 16 with their foil ends projecting in the direction of extensions 17 and 18 respectively, and spaced therefrom. The sides of the sections 5 may bear directly against the sides of the member 16 but insulating liners may be inserted between the bearing surfaces if desired. The support for the condenser is completed by another U-shaped member 20 which bears against the top 10 section of the condenser and is held in place by the bent-over ends 21 and 22 of member 16. Members 16 and 20 thereby form a clamp for the condenser sections which are preferably held under pressure while the ends 21 and 22 are bent-over. Liners 23 provide insulation for the clamp.

The can 1 is made sufficiently long to provide spaces between the foil ends and the walls of the can so that, when the clamped condenser is within the can, the projections 17 and 18 keep the 20 foil ends in spaced relation to the walls. Lateral movement of the condenser is prevented by the sides of the member 16 and its projections 17 and 18. The portions of the members 16 and 20 which project above the condenser prevent movement of the condenser in a vertical direction.

The condenser sections are electrically connected by metallic strips, such as 24, extending from one section to another in the spaces between the foil ends and the walls of the container, such connections being made before the condenser is inserted in the can. In Fig. 1 all of the sections are connected in parallel, but series or series-parallel connections may be used or the sections may be connected to form separate groups.

The members 16 and 20 provide and maintain sufficient space between the top of the condenser and the top of can 1 for terminals, such as 25 and 26, and leads, such as 27 and 28, electrically connecting the terminals with the condenser. The terminals 25 and 26 are preferably secured to the top of the inner can 1 and insulated therefrom by means of insulating washers 29; holes 30 in the can being made considerably larger than the terminals. The washers 29 are sealed by cement or varnish. The top of the outer can 2 is provided with openings 31 and is otherwise adapted to accommodate the washers and terminals. Suitable connecting lugs 32 are secured to the terminals for convenience in making electrical connections.

The above mentioned spaces between the top and sides of the condenser 5 and the can 1 are made no longer than is necessary to provide 55 room for the connecting strips and leads, thereby conserving space and oil. The fixed spacing provided by the condenser clamp permits small clearances with assurance that accidental contact of conductive parts with the walls will 60 not occur.

In assembling the condenser, the can 1 with the condenser and its clamp therein and with the terminals affixed, is sealed up except for two small holes such as 33. The can is then filled 65 with hot oil (approximately 160° F.) through one of these holes, the air escaping through the other hole. The can is filled to within about $\frac{1}{8}$ th inch of the top and, while the oil is still hot, the holes are soldered over. When the oil cools a slight 70 vacuum is created thereby permitting subsequent expansion and contraction of the oil without creating excessive pressure in the can and eliminating the necessity for a breather opening.

75 In a double-walled container, as above de-

scribed, the cushioning effect between the two walls absorbs and distributes mechanical shocks, thereby preventing injury to the soldered seams of the inner wall so that they remain oil tight even though the device be subjected to mechanical abuse. The double-wall construction also prevents accidental puncture of the inner wall by sharp instruments, a frequent cause of trouble with "tin can" type containers. The protection afforded by the outer walls permits the use 10 of thin metal for the oil tight portion of the container even though the enclosed electrical device has considerable size and weight. These advantages are obtained with a double-walled container having the same or smaller outside dimensions than a single walled container of the same 15 inside dimensions because of the space required for upstanding seams and thick welds to make the latter container oil tight.

The manufacturing cost of such a double-walled container is less than the cost of the heavy single-wall type due principally to the simplicity of its parts and the ease with which they are joined. The condenser can be sealed in the inner can without excessive heating thereof 20 because of the small heat capacity of the thin metal walls. Joining the parts of the other enclosure presents no difficulty when the joints need not be oil tight, and no heat is required to complete the outer enclosure after the condenser is 25 placed therein. As an example, a heavy metal can of a certain size and made oil tight costs \$2.50 plus the labor required to seal the cover after the condenser is inserted therein, which operation is complicated by the large amount of 30 heat required and consequent danger to the condenser. Compared to this cost, a double-walled container of the same size costs only 30 or 31 cents, of which 12 or 13 cents is the cost of the inner can and 18 cents is the cost of the 40 outer enclosure.

The manufacture of a container in accordance with this invention requires less expensive equipment and such equipment is more readily adapted to different sized containers than the equipment required for the manufacture of oil tight, 45 heavy metal containers.

I claim:

1. A container for an electrical condenser comprising an inner liquid-tight thin sheet-metal casing, an outer casing of relatively thick sheet metal and a meltable compound interposed between the casings and filling any open spaces between them and substantially adhering to their opposite faces.

2. An electrical condenser comprising an inner liquid-tight thin sheet-metal casing holding the condenser elements therein, an outer casing of relatively thicker sheet metal and slightly larger than and surrounding the inner casing, and a wax-like compound partially or wholly filling the space between the two casings and constituting a unitary filler means.

3. An electrical condenser comprising an inner liquid-tight, thin sheet-metal casing holding the condenser elements therein, an outer casing of relatively thicker sheet metal and slightly larger than and surrounding the inner casing, and a compound sufficiently liquid to be poured into said space between the two casings and becoming solid at normal temperature so as to constitute a unitary means for securely positioning and protecting the inner thin metal casing.

4. An electrical condenser comprising a con-

- denser body, a container for the condenser body formed of thin readily bendable metal having edge portions bent into tight-fitting engagement with adjacent portions of the container to form 5
5 seams, sealing means continuously sealing all seams to provide a liquid-tight casing, said metal having sufficient rigidity to provide a self-supporting manipulable container unit; and an unsealed outer protective casing of relatively rigid 10
10 shock-resistant metal enveloping and closely fitting the container.
5. An electrical condenser comprising a condenser body, a container for the condenser body formed of thin readily bendable and solderable 15
15 metal having edge portions crimped together to form seams, solder continuously sealing all seams of the container to provide a liquid-tight casing, said metal having sufficient rigidity to provide a self-supporting manipulable container 20
20 unit; and an unsealed outer protective casing of relatively rigid shock-resistant metal enveloping and closely fitting the container.
6. An electrical condenser comprising an hermetically sealed container formed of thin readily bendable metal, a condenser body mounted 25
25 in the container and completely supported thereby, said metal having sufficient rigidity to provide, in combination with the condenser body mounted therein, a self-supporting manipulable 30
30 container unit; and an unsealed outer protective casing of relatively rigid shock-resistant metal enveloping and closely fitting the container.
7. An electrical condenser comprising an hermetically sealed container formed of thin readily bendable metal, a condenser body mounted 35
35 in the container and completely supported thereby, said metal having sufficient rigidity to provide, in combination with the condenser body, a self-supporting manipulable container unit; an 40
40 unsealed outer protective casing of relatively rigid shock-resistant metal enveloping and closely fitting the container, and insulated terminals connected to the condenser body and accessible from the exterior of the protective casing.
- 45 8. An electrical condenser comprising an hermetically sealed container formed of thin relatively flexible metal, a condenser body mounted in the container, said metal having sufficient rigidity to provide, in combination with the condenser body, a self-supporting manipulable container unit; and an outer protective casing of 45
45 relatively rigid metal enveloping and closely fitting the container, the protective casing being formed of a plurality of sections joined at spaced 50
50 points to provide an unsealed mechanically strong casing.
9. An electrical condenser comprising a condenser body, a container for the condenser body formed of thin readily bendable metal having 55
55 edge portions bent into tight-fitting engagement with adjacent portions of the container to form seams, sealing means continuously sealing all seams to provide a liquid-tight casing, said metal having sufficient rigidity to provide a self-supporting manipulable container unit; and an outer protective casing of relatively rigid metal enveloping and closely fitting the container, the protective casing comprising a body portion shaped to fit closely and substantially continuously over the sides and one end of the container, arranged to permit endwise insertion of 60
60
- the container, and an end section adapted for connection to the body portion in position to cover the exposed end of the inner container after insertion thereof in the body portion, the outer casing sections being arranged to provide 5
5 a mechanically strong unsealed casing for the container.
10. An electrical condenser comprising a condenser body, a container for the condenser body formed of thin readily bendable metal having edge portions bent into tight-fitting engagement with adjacent portions of the container to form 10
10 seams, sealing means continuously sealing all seams to provide a liquid-tight casing, said metal having sufficient rigidity to provide a self-supporting 15
15 manipulable container unit; an unsealed outer protective casing of relatively rigid metal enveloping and closely fitting the container, and cushioning means arranged between the casing and the container in position to prevent movement of the container in the casing, said means comprising yieldable material in extended contact with the walls of the container body to distribute over a substantial area of the container 20
20 impacts transmitted through the casing. 25
11. An electrical condenser comprising a condenser body, a container completely enclosing the body, and means for mounting the condenser body in the container, comprising flat members engaging the top, bottom and opposite sides of the condenser body and positioned in flatwise contact with the bottom and two opposite sides of the container, extending into engagement with the other opposite sides of the container at the bottom to maintain the condenser body 30
30 against movement within the container.
12. An electrical condenser comprising a condenser body comprised of a plurality of flattened condenser rolls, a container, and a clamping frame for mounting the condenser body in the container, said frame comprising members of flat material extending along the bottom, top and opposite sides of the condenser body and fitting flatwise against two opposite sides of the container over a substantial portion of the area 40
40 thereof, arranged to provide a reinforcement for the container, the bottom of the frame being in extended flatwise contact with the bottom of the container and arranged to provide a reinforcement therefor, said bottom being provided 45
45 with upturned ends engaging the other sides of the container and arranged to maintain said sides in spaced relation to the ends of the condenser rolls. 50
13. An electrical condenser comprising a condenser body, a container, and a clamping frame for mounting the body in the container, said frame comprising a U-shaped member of sheet material extending along the bottom and opposite sides of the condenser body and in substantially continuous flatwise engagement with the juxtaposed sides of the container, a bottom member of sheet material extending across the bottom of the U-shaped member and having upturned ends engaging the other sides of the container in position to maintain the condenser body in spaced relation thereto, the bottom of the frame being in substantially continuous flatwise engagement with the bottom of the container. 55
